DISPENSER

Ralph L. Stephenson, Berkeley, Calif.

Application September 11, 1957, Serial No. 47,703

Term of patent 14 years

(Cl. D62—2)

The dominant features of the design reside in the portion in full lines.

I claim:

The ornamental design for a dispenser, as shown and described.
